SHUTTER BLIND SLAT HOLDER

Albert J. Olson, Tarpon Springs, Fla.

Application July 29, 1949, Serial No. 107,473

1 Claim. (Cl. 160—368)

1

This invention relates to awning shutters, and more particularly to an awning shutter which is an efficient ventilator, and at the same time satisfactorily shades the room from the direct rays of the sun.

This invention is an improvement over the shutter blind of my copending application, Serial No. 7,413, filed February 10, 1948.

The object of the invention is to provide an improved bearing arm for improving the operation and construction of the shutter blind described in detail in my copending application, Serial No. 7,413.

Another object of the invention is to provide a bearing arm for a shutter blind, the bearing arm including a plurality of slots through which extend the ends of the flexible slats or blades whereby the flexible slats will lie snugly together when the shutter blind is moved to its closed position.

A further object of the invention is to provide a shutter bearing arm which is extremely simple and inexpensive to manufacture.

Other objects and advantages will be apparent during the course of the following description.

In the accompanying drawings forming a part of this application, and in which like numerals are used to designate like parts throughout the same:

Figure 1 is a sectional view taken on the line 1—1 of Figure 2;

Figure 2 is a sectional view taken on the line 2—2 of Figure 1;

Figure 3 is a perspective view of the shutter bearing arm according to the present invention;

Figure 4 is a sectional view taken on the line 4—4 of Figure 2.

Referring in detail to the drawings, the numeral 10 designates a portion of a conventional window sash or frame which is adapted to be moved toward and away from a window. Arranged adjacent the window sash 10 is an operating rod 11 which, when actuated in the manner described in detail in my copending application, will move the slats or shutters 12 into and out of their closed positions.

The present invention is directed to a novel bearing arm which is designated generally by the numeral 13, and the bearing arm 13 is preferably fabricated of a single suitable piece of material. The bearing arm 13 includes a body portion 14 which has a pair of longitudinally-extending, spaced parallel slots 15 and 16 extending therethrough. A portion of the slats 12 is adapted to be trained through the slots 15 and 16 in the manner shown in Figure 4.

Projecting from the body portion 14 and arranged angularly therewith is a support portion 17 which is provided with a pair of spaced openings 18 and 19. A pin 20 projects through the opening 18 and into engagement with the window

sash 10, whereby a pivotal connection is provided between the bearing arm and the window sash 10. A similar pin 21 projects through the other opening 19 and into engagement with the operating rod 11, so that the bearing arm is also pivotally connected to the operating rod 11.

From the foregoing it is apparent that a bearing arm 13 has been provided which is especially suitable or adapted to be used with the awning structure of my copending application. Thus, the flexible shutters or slats 12 that are made of fabric such as heavy canvas or the like, are arranged so that a portion of the slats 12 is trained through the slots 15 and 16 in the bearing arm 13. It is to be understood that a plurality of the bearing arms 13 are used in each awning structure. The pins 20 and 21 pivotally connect the bearing arm 13 to the window sash 10 and the operating rod 11. Then, upon movement of the operating rod 11, as described in my copending application, all of the bearing arms 13 will be pivoted so that the slats 12 can be moved into and out of closing position. Thus, by proper movement of the operating rod 11, the position of the shutters or slats 12 can be adjusted so that any desired amount of sunlight or ventilation can be permitted to enter a room.

I claim:

30 In a shutter blind having a bearing arm including a body portion provided with a pair of spaced parallel longitudinally extending slots and a support portion arranged angularly with respect to said body portion and projecting therefrom to the improvement comprising a flexible slat having one end trained through one of said slots in one direction then over the body portion and around the edge thereof to be trained through the other of said slots and then through the first of said slots beneath the portion in said first slot to terminate in a position at right angles to the body portion, the remainder of the slat then overlying that portion thereof that is trained through the slots to extend outwardly of the body portion to terminate in the same plane with the body portion.

ALBERT J. OLSON.
